(57) **CLAIM**

The ornamental design for a bead seal diaphragm, as shown and described.

DESCRIPTION

FIG. 1 is an elevation view of a bead seal diaphragm; FIG. 2 is a bottom perspective view of the bead seal diaphragm;

FIG. 3 is a top perspective view of the bead seal diaphragm;

FIG. 4 is a top plan view of the bead seal diaphragm;

FIG. 5 is a bottom plan view of the bead seal diaphragm;

FIG. 6 is an elevation cross-sectional view of the bead seal diaphragm taken in the direction of line 6-6 in FIG. 4;

FIG. 7 is a top perspective cross-sectional view of the bead seal diaphragm taken in the direction of line 6-6 in FIG. 4; and,

FIG. 8 is a bottom perspective cross-sectional view of the bead seal diaphragm taken in the direction of line 6-6 of FIG. 4.

1 Claim, 6 Drawing Sheets
